ATTORNEY

UNITED STATES PATENT OFFICE

HENRY A. ULRICH, OF LOS ANGELES, CALIFORNIA

STEAM BOILER

Application filed July 29, 1932 Serial No. 625,989.

This invention relates to steam boilers of the water tube type adapted for either land or marine use, and has for the primary object the provision of a device of the above stated character whereby the water may have rapid and unrestricted circulation to permit quick generation of steam in maximum amounts with a minimum consumption of fuel.

Another object of this invention is the provision of upper and lower pairs of drums connected by pairs of banks of tubes so constructed as to permit free circulation of the water and preventing formation of steam pockets one pair of banks of tubes being arranged in direct contact with the combustion gases from the fire box and inter-crossing while the other pairs of banks of tubes diverge downwardly within passages for the gases after acting on the inter-crossing banks of tubes to assure maximum use of the heat.

A further object of this invention is the employment of a pair of steam drums instead of a single drum to reduce turbulence of the water in said drums and the latter having multiple steam take off tubes the entire length thereof reducing the tendency to lift water from the drums.

With these and other objects in view, this invention consists in certain novel features of construction, combination and arrangement of parts to be hereinafter more fully described and claimed.

For a complete understanding of my invention, reference is to be had to the following description and accompanying drawings, in which

Figure 1 is a transverse sectional view illustrating a steam boiler constructed in accordance with my invention.

Figure 2 is a side elevation partly in section illustrating the same.

Referring in detail to the drawings, the numeral 1 indicates a casing or housing in which is constructed a fire box 2 receiving heat from a series of burners 3 adapted for burning gaseous or liquid fuel. Parallel steam drums 4 and 5 are arranged in the upper portion of the casing 1 directly above the fire box. Lower drums 6 and 7 are arranged in the casing 1 adjacent the fire box

and are connected to the drums 4 and 5 respectively by banks of downwardly diverging tubes 8 and 9. The drums 6 and 7 are connected to the drums 5 and 4 respectively by banks of tubes 10 and 11. The tubes 10 and 11 inter-cross each other as shown in Figure 1 directly above the fire box rendering a formation of substantially X-shape so that the products of combustion and heat from the fire box may play directly against the banks of tubes 10 and 11. Partitions or deflectors 12 are arranged between the banks of tubes 8 and 10 and 9 and 11 and cooperate with the partitions 12' in forming chambers or passages 13 in which the banks or tubes 8 and 9 are located. The combustion gases after passing upwardly are directed downwardly through the passages 13 and into upwardly converging passages 14 communicative with flues 15 that lead to the usual smoke stack. The upwardly converging passages 14 are formed by the partitions 12' and the walls of the casing. It is to be understood that the walls of the casing are suitably lined with heat resisting material.

A deflector 16 is arranged between the drums 4 and 5 above the inter-crossing of the tubes 10 and 11 for aiding in deflecting the heat and products of combustion downwardly through the passages 13. The drums are connected by a wall 17 forming a closure for the upper part of the heat chamber of the furnace and arranging the major portions of the drums 4 and 5 within the heat chamber. The path of travel of the heat and fumes from the fire box is as indicated by the arrows in Figure 1.

A steam collecting drum 18 is located between the drums 4 and 5 and is connected to the latter by a series of steam tubes 19 whereby the steam generated within the drums 4 and 5 may readily pass into the collecting drum 18 and thence into a super-heated steam outlet header 20 connected to the steam collecting drum 18 by a series of removable tubes 21 extending downwardly through the banks of tubes 11 and 12 to form superheaters which comes in direct contact with the heat and products of combustion as they rise from the

fire box. The steam collecting drum 18 is provided with a suitable safety valve 22.

Feed water heaters 23 are arranged within the passages 14 and are fed with water

5 through inlet pipes 24 which communicate therewith at the upper portions thereof. Outlet pipes 25 are in communication with the lower portions of the feed water heaters 23 and are in turn connected to the drums 4 10 and 5. The pipes 25 are provided with control valves 26, thus it will be seen that the water is pre-heated and then fed into the drums 4 and 5 whence it circulates downwardly through the banks of tubes 8 and 9 15 into the drums 6 and 7. The heated water rises from the drums 6 and 7 through the banks of tubes 10 and 11 to the drums 5 and 4, becoming highly heated to generate steam in said drums which passes into the steam collecting drum 18, thence into the super-heated steam outlet header or drum 20.

Cooling tubes 27 are connected to the drums 6 and 7 and extend downwardly on the inside 25 of the walls of the fire box to cool said walls and are connected to bottom drums 28 that are in turn connected to the drums 6 and 7 by tubes 29. The bottom drums 28 are provided with clean-out ports closed by removable covers 30, whereby sediment and other 30 foreign matter may be cleaned therefrom.

The feed water heaters each are constructed of a series of compartments as shown in Figure 1 in which are arranged series of communicative tubes so that the 35 water circulating downwardly prior to entering the steam drums may be effectively pre-heated.

The boiler may be heated by fuel other than liquid or gaseous fuel if desired.

40 While I have shown and described the preferred embodiment of my invention, it will be understood that minor changes in con-

struction, combination and arrangement of parts may be made without departing from the spirit and scope of my invention, as claimed.

Having thus described my invention, what I claim is:—

A steam boiler comprising a casing, a fire box in said casing, means for heating the fire box, a pair of parallel steam drums arranged in the casing directly above the fire box, lower drums arranged in the casing adjacent the fire box, downwardly and outwardly extending banks of tubes connecting the steam drums to the lower drums, diagonally extending and inter-crossing banks of tubes connecting the lower drums to the steam drums and arranged directly in the path of combustion from the fire box, deflectors arranged between the first and second banks of tubes, deflectors arranged between the first mentioned deflectors and the walls of the casing for forming downwardly and upwardly extending passages with the first mentioned banks of tubes arranged in the downwardly extending passages, means connecting the upwardly extending passages to a smoke stack, feed water heating means in the upwardly extending passages and connected to the steam drums, a steam collecting drum arranged in the casing between the steam drums, a series of tubes connected to the steam drums throughout the lengths thereof and to the steam collecting drum, a superheated steam outlet header arranged below the steam collecting drum, and superheated tubes connecting the steam collecting drum with the super-heated steam outlet header and extending downwardly through the second mentioned banks of tubes.

100 In testimony whereof I affix my signature.

105 HENRY A. ULRICH.
